UNITED STATES PATENT OFFICE.

CHARLES THATCHER HATCH, JR., OF ALBION, MICHIGAN, ASSIGNOR TO UNION STEEL PRODUCTS COMPANY, LTD., OF ALBION, MICHIGAN.

LUGGAGE CARRIER FOR AUTOMOBILES.

Application filed January 8, 1923. Serial No. 611,347.

To all whom it may concern:

Be it known that I, CHARLES THATCHER HATCH, Jr., a citizen of the United States, residing at Albion, county of Calhoun, State 5 of Michigan, have invented certain new and useful Improvements in Luggage Carriers for Automobiles, of which the following is a specification.

This invention relates to improvements in 10 luggage carriers for automobiles.

The main object of the invention is to provide an improved collapsible luggage carrier adapted for attachment to the running board of an automobile which may be 15 compactly collapsed and is easily erected or extended and when extended and secured to the running board forms a very firm support or carrier.

Further objects, and objects relating to 20 structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing, forming a part of this application, in which:

30 Fig. I is a rear or inside elevation of my improved luggage carrier in collapsed position, the extended or erected position of certain of the parts being indicated by dotted lines.

35 Fig. II is a vertical section on a line corresponding to line 2-2 of Fig. I with the end arms in erected position, the carrier being illustrated as mounted upon a running board.

40 Fig. III is an enlarged detail horizontal section on a line corresponding to line 3-3 of Fig. I.

45 Fig. IV is an enlarged detail vertical section on a line corresponding to line 4-4 of Fig. I.

Fig. V is a detail horizontal section on a line corresponding to line 5-5 of Fig. II showing details of the mounting for the end supporting arm.

50 In the drawings similar reference characters refer to similar parts throughout the several views and the sectional views are taken looking in the direction of the little arrows at the ends of the section lines.

55 Referring to the drawings, I provide a

pair of uprights 1 and an intermediate upright 2, these uprights being of channel cross section, the end uprights being arranged with their channels facing outwardly. These uprights are provided with 60 clamps 3 having shanks 4 secured within the channels of the uprights. These clamps are adapted to engage the footboard of an automobile, as 5. The end uprights are provided with longitudinal slots 6 adjacent their upper ends, while the intermediate upright has a longitudinal slot 7 at its upper end and a longitudinal slot 8 at its lower end, these slots being shown by dotted lines in Fig. I.

I provide a plurality of bars 9 which are 70 connected by pivots 10 to provide a lazy tongs structure. The outer ends of the end bars of this lazy tongs structure are provided with relatively short longitudinal slots 11. Brackets 12 are secured at the lower 75 ends of the end uprights to project inwardly therefrom and are provided with pins or pivots 13 which engage the slots 11 in the downwardly directed end bars of the lazy tongs structure. At the upper ends of the 80 end uprights are slides 14 which are slidably secured to the upright by the pins 15. These slides carry pins 16 which engage the slots 11 in the upwardly directed end members of the lazy tongs structure. The pivots 85 10 of intermediate bars engage in the slots 7 and 8 of the intermediate upright, thereby supporting the central portion of the lazy tongs structure which is a desirable feature 90 when it is fully extended.

To support articles arranged in the carrier against lateral movement I provide arms 17 which are secured by the pivots 18 to the end bars to collapse on the inner side thereof, spring washers 19 being provided for frictionally supporting the arms in their adjusted positions.

With this arrangement of parts I secure a structure which is very strong and secure when mounted upon the vehicle and may be 100 easily collapsed and erected with little likelihood of the parts wedging or binding.

Having thus described my invention, what I claim as new and desire to secure by Letters Patent, is:

1. In a folding luggage carrier, the combination of a pair of uprights of channel cross section with their channels facing outwardly and having longitudinal slots 105 in their webs adjacent their upper ends, said 110

- uprights being provided with running board clamps, a plurality of bars disposed and pivotally connected to provide a lazy tongs structure, the outer ends of the end bars being provided with relatively short longitudinal slots, inwardly projecting brackets disposed at the lower ends of the uprights and provided with pins engaging the slots at the lower ends of the downwardly projecting end bars, and inwardly projecting slides slidably engaging said slots at the upper ends of said uprights and having pins engaging the slots in the upper ends of the upwardly projecting end bars.
2. In a folding luggage carrier, the combination of a pair of uprights of channel cross section with their channels facing outwardly and having longitudinal slots in

their webs adjacent their upper ends, said uprights being provided with running board clamps, a plurality of bars disposed and pivotally connected to provide a lazy tongs structure, the outer ends of the end bars being provided with relatively short longitudinal slots, inwardly projecting brackets disposed at the lower ends of the uprights and provided with pins engaging the lower ends of the downwardly projecting end bars, and inwardly projecting slides slidably engaging said slots at the upper ends of said uprights and having pins engaging the upper ends of the upwardly projecting end bars.

In witness whereof I have hereunto set my hand and seal.

CHARLES THATCHER HATCH, Jr. [L.S.]
